PENCIL HOLDER

Elizabeth Friedel, New York, N. Y.

Application April 23, 1951, Serial No. 14,915

Term of patent 7 years

(Cl. D74—1)

To all whom it may concern:

Be it known that I, Elizabeth Friedel, a citizen of the United States, residing at New York, in the county of New York and State of New York, have invented a new, original, and ornamental Design for a Pencil Holder, of which the following is a specification, reference being had to the accompanying drawing, forming part thereof.

Fig. 1 is a front perspective view of a pencil holder embodying my new design; and

Fig. 2 is a side elevation thereof.

The bottom of the pencil holder is plain.

I claim:

The ornamental design for a pencil holder, as shown and described.

ELIZABETH FRIEDEL.
